UNITED STATES PATENT OFFICE.

DANIEL KOPS, OF NEW YORK, N. Y.

APPAREL-CORSET.

1,399,486.

Specification of Letters Patent. Patented Dec. 6, 1921.

Application filed November 16, 1920. Serial No. 424,341.

To all whom it may concern:

Be it known that I, DANIEL KOPS, a citizen of the United States, residing in the borough of Manhattan, city, county, and State 5 of New York, have invented an Improvement in Apparel-Corsets, of which the following is a specification.

This invention relates to an apparel corset and particularly to that type of apparel 10 corset in which in conjunction with self-reducing straps at the lower front portions of the corset body halves there are also employed abdominal supporting straps extending from the front steel portions rearwardly 15 to points forward of the hip sections to support the abdomen of the wearer. I am aware that heretofore various forms of apparel corsets have been proposed in which self-reducing straps have been employed and 20 with which, as in the present case, there are associated depending hose supporters. I am also aware that heretofore various forms of apparel corsets have been employed in which there are abdominal supporting straps ex- 25 tending from the front steel sections rearwardly to points forwardly of the hip sections. In all these instances, however, the self-reducing straps and the hose supporters associated therewith have been employed to 30 produce the self-reducing effect and the proper formation of the garment when in use, and abdominal supporting straps have been employed to support as well as to reduce the abdomen of the wearer, but in these 35 latter structures the supporting straps have been designed for use in the ordinary average case where such a corset is advisable and to this end these supporting straps at their forward edges have not been employed on 40 the inner side of the garment and made to extend below the front steel sections of the garment. The object of the present invention is to provide a garment more especially adapted for use in special cases in which the 45 lower portion of the abdomen is to be supported and reduced because of the superfluous flesh accumulated at this place, or because of the prolapse condition of the muscles and lower abdominal organs made so 50 from any cause whatsoever. Consequently in carrying out the present invention the tension straps employed are preferably made of elastic material and are secured in the inner side of the garment in such a manner

that the lower forward ends thereof are 55 placed considerably below the lower ends of the front steel sections and the forward edges extend upwardly therefrom to the upper portion of the abdomen and are connected to the front steel sections, while the lower edges 60 thereof are so placed as to conform to and lie directly in the groin section of the wearer. These straps extend rearwardly from the front steel sections on the inner side of the garment and are attached at their opposite 65 edges at points forward of the hip sections, while the self-reducing straps employed are connected to the garment preferably along the same lines of stitching that the rearward edges of the tension straps are secured 70 and extend forwardly and are adjustably connected to the front steels as is customary in order to overlie a portion of the supporting straps, and to act in conjunction therewith in producing the usual self-reducing 75 effect.

The garment made in accordance with my invention is shown in the accompanying drawing, in which,

Figure 1 is a perspective view illustrating 80 the use of the garment, and

Fig. 2 is an enlarged elevation of the inner side of one of the corset body halves.

By referring to the drawing it will be seen that in the construction of the corset 85 garment made in accordance with this invention the same preferably comprises corset body halves indicated at 10 and 11 respectively and both provided with a depending skirt 12 and as usual is fitted with front 90 steels 13 having clasps 14 by which the halves of the garment are connected at the front of the body as well as eyelets 15 along the back edges for the adjusting laces by which, as is also customary, the garment is 95 adjusted to position on the body of the wearer.

The halves of the garment made in accordance with this invention are made in a similar manner but of course with the parts 100 in reversed positions and consequently but one part of the corset structure will be hereinafter particularly described. The front or forward portion of the skirt member terminates at a point short of the front edge 105 of the garment as is indicated at 16 and at this place the cut away portion of the skirt is indicated at 16'. The front steel section

of the garment is extended as indicated at 17 for an appreciable distance below the lower end of the front steel, terminating, however, above the lower edge of the skirt member and at a point approximately midway between the lower edge of the front steel and the lower edge of the skirt member. This extension 17 furthermore is fitted with a hose supporter 18 in the usual manner. In carrying out the invention I also employ a supporting tension strap made of elastic or other suitable yielding material which is indicated at 19. This strap member 19 is secured to the front steel section of the garment along a line of stitching indicated at 20 and as will be noted from the drawing extends from the lower extremity of the extension 17, that is an appreciable distance below the lower end of the front steel to a point 21 which is approximately the upper portion of the abdomen, this edge of the strap being relatively long. The strap is placed on the inner side of the garment and extends rearwardly. Along its upper edge it tapers downwardly, while along its lower edge it tapers upwardly and at the edge opposite that secured by the line of stitching 20 the strap is secured to the body of the corset forward of the hip section thereof, this line of stitching by which the opposite edge is secured in the garment being indicated at 22. The downwardly tapering upper edge of the strap is indicated at 23 and the upwardly tapering edge of the strap is indicated at 24 and the strap is so placed in the garment at the inner side thereof that this lower edge thereof fits directly into the groin section of the wearer so as to adequately support the superfluous flesh in the lower portion of the abdomen or the lower abdominal muscles or abdominal organs which for any cause whatsoever may have become prolapse and hence require the support which the strap so placed is adapted to give.

In conjunction with the supporting strap hereinbefore described I also employ a self-reducing strap 25. At one edge this self-reducing strap is connected to the body of the garment forward of the hip section and preferably by the same line of stitching 22 by which the rearward edge of the supporting strap 19 is secured in the garment. The self-reducing strap 25 extends forwardly and downwardly, and below the line of stitching 22 the rearward edge 26 of the strap is entirely free from the body of the garment and the skirt member thereof. At the forward edge of the self-reducing strap the same is provided with eyelets 27 adapted to be engaged by a stud 28 fixed in the lower end of the corresponding front steel to secure and adjust the self-reducing strap to position for use. It will be understood that the self-reducing strap performs the

usual functions of this member as shown and described in various Letters Patent heretofore granted to me while acting in conjunction with the tension strap to assist the latter in also performing its functions.

The depending portion of the self-reducing strap extends to the lower edge of the skirt member and is attached thereto along a line of stitching indicated at 29 which also secures in the garment a hose supporter 30, the lower front edge of the skirt, the hose supporter strap and the lower depending edge of the self-reducing strap being preferably all connected together by the same line of stitching as indicated at 29 so that the depending portion of the self-reducing strap is maintained in place with the upper portion thereof overlying the lower portion of the body of the garment and also that part of the supporting strap 85 which lies beneath the same.

In order to connect the extensions 17 of the front steel sections, one of these extensions may be provided with a hook 31 and the other with a catch 32, the one to be engaged by the other to connect and secure these extensions in position for use.

I claim as my invention:

1. In an apparel corset comprising corset body halves having skirt members and in each corset body half, a front steel, an extension of the corset body half below the lower end of the front steel, and a supporting strap secured at one edge adjacent the front steel and extending from the lower end of the said extension to the upper portion of the abdomen and also extending rearwardly on the inner side of the garment and attached at its opposite edge to the body of the garment forward of the hip section so that the lower edge of the supporting strap lies directly in the groin section of the wearer, whereby the adjustment of the garment to position on the body places a tension on the said supporting strap causing the strap to conform to the lower portions of the abdomen to act as a support for the same.

2. In an apparel corset comprising corset body halves having skirt members and in each corset body half, a front steel, an extension of the corset body half below the lower end of the front steel, and a supporting strap secured at one edge adjacent the front steel and extending rearwardly on the inner side of the garment with its upper edge tapering downwardly and its lower edge tapering upwardly with the edge opposite that secured to the front steel section connected to the body of the garment forward of the hip section so that the lower edge of the supporting strap lies directly in the groin of the wearer, whereby the adjustment of the garment to position on the body places a tension on the said support-

ing strap causing the strap to conform to the lower portions of the abdomen to act as a support for the same.

3. In an apparel corset comprising corset body halves having skirt members and in each corset body half, a front steel, an extension of the corset body half below the lower end of the front steel, an elastic tension strap secured at one edge adjacent the 10 front steel and extending from the lower end of the said extension to the upper part of the abdomen and also extending rearwardly on the inner side of the garment and attached at its opposite edge to the 15 body of the garment forward of the hip section so that the lower edge of the supporting strap lies in the groin section of the wearer, whereby the adjustment of the garment to position on the body places a tension 20 on the said supporting strap causing the strap to conform to the lower portions of the abdomen to act as a support for the same and a self-reducing strap connected at one edge forward of the hip section and 25 adjustably connected to the front steel section so as to overlie the lower portion of the tension strap and to coat therewith in producing a self-reducing effect in the use 30 of the garment.
4. In an apparel corset comprising corset body halves having skirt members and in each corset body half, a front steel, an extension of the corset body half below the lower end of the front steel, an elastic ten-

sion strap secured at one edge adjacent the 35 front steel from the lower end of said extension to the upper part of the abdomen and extending rearwardly on the inner side of the garment with its upper edge tapering downwardly and its lower edge tapering upwardly, and with the edge opposite 40 that secured to the front steel section connected to the body of the garment forward of the hip section so that the lower edge of the supporting strap lies directly in the 45 groin of the wearer, whereby the adjustment of the garment to position on the body places a tension on the said supporting strap causing the strap to conform to the lower portions of the abdomen to act as 50 a support for the same and a self-reducing strap secured to the body of the garment along the same line of stitching that secures the rearward edge of the elastic tension 55 strap thereto, the said self-reducing strap being otherwise free from the body of the garment but connected at its lower end to the lower forward edge of the skirt section and adapted also to be adjustably connected to the lower portion of the front steel to 60 coat with the tension strap and thereby assist in supporting the lower portions of the abdomen and producing a self-reducing effect.

Signed by me this 1st day of November, 65
1920.

DANIEL KOPS.
